UNITED STATES PATENT OFFICE

KENLY C. BUGG, OF FARMINGTON, MISSOURI, ASSIGNOR TO OZARK NOVELTY COMPANY, OF FARMINGTON, MISSOURI, A CORPORATION OF MISSOURI

COIN CONTROL MECHANISM

Application filed April 22, 1931. Serial No. 531,887.

This invention relates to coin control mechanism; and also has reference to mechanism for separating slugs and the like from the coins and for preventing control of the mechanism by such slugs.

In my copending application, Serial No. 514,349, filed February 9, 1931, for game device, the invention there disclosed comprised a table, in combination with mechanism controlling the accessibility of balls adapted to be used in playing the game on the table, and coin controlled apparatus for controlling said mechanism and requiring the deposit of a coin in the coin controlled apparatus before the said coin controlled apparatus could be operated to control the mechanism causing the balls to pass to an accessible position.

It has been demonstrated by experience in connection with this invention and other devices including vending machines that attempts are frequently made to defraud the machines by use of slugs of about the size of the coins required to operate the machine. The use of these fraudulent slugs for these dishonest purposes has grown enormously, so that it is necessary to make provision to prevent operation of the machines and other devices by use of the slugs.

An object of the present invention is to provide a coin controlled apparatus for use in connection with the game device constituting the subject matter of my said application, as well as for other uses, whereby the operation or adjustment of the devices controlling operation of the discharge mechanism of the machines by use of slugs is prevented, and whereby the spurious slugs and the like are separated from the coins of proper value and thrown out of the way so that they will not interfere with the proper operation of the device when a coin of proper value is inserted.

Various other objects of the invention, and its adaptability to many uses, will appear from the following description, reference being made to the accompanying drawings, in which—

Fig. 1 is an end elevation of a game table having my invention mounted in connected therewith.

Fig. 2 is an enlarged sectional view showing the chutes for the balls used in playing the game, and the coin control locking device for preventing the balls from passing to an accessible position until a coin of proper value has been inserted in the apparatus.

Fig. 3 is an inner side elevation of the coin control and slug removing device.

Fig. 4 is a vertical sectional view of the device.

Fig. 5 is a vertical transverse sectional view showing numerous elements of the device in their unoperated or starting positions.

Fig. 6 is a view similar to Fig. 5 showing the parts in their operated positions.

Fig. 7 is an enlarged sectional view on the line 7—7 of Fig. 4.

The game device in connection with which the invention is shown for illustrative purposes is a table comprising a top 1 (Fig. 2) having a ledge 2 rising from the marginal portions of the top 1. The top 1 is provided with one or more holes 3 (Fig. 2) through which the balls 4 pass when successful plays are made.

These balls 4 pass into a chute comprising an inclined bottom wall 5. The balls 4 roll along the bottom wall 5 of the chute until the ball in front engages an abutment that serves to stop and retain the entire series of balls and prevent the balls from passing onto the inclined wall 6 which constitutes a support from which the balls may be removed through an opening 7. Thus, until the balls can pass downwardly along the wall 6 to a position opposite the opening 7, it is impossible to remove the balls from their concealment or to play the game by use of the balls.

My present invention comprises an abutment lever 8 mounted on a pivot 9 and extending downwardly so as to form an abutment for the balls, as stated and will be understood by reference to Fig. 2 of the drawings, so that the balls cannot pass to accessible position opposite the opening 7 without operating the lever 8.

A latch device for the lever 8 is provided so as to hold said lever in position to stop the balls and prevent the balls from passing to ac-

cessible position opposite the opening 7 until the latch device is operated by a coin of proper value deposited in the apparatus. This latch device comprises an angular lever 5 including an arm 10 mounted on a pivot 11 (Fig. 4) and designed and adapted to engage in a notch 12 in the upper end of the lever 8 and thereby latch said lever 8, against operation until the latch 9 is removed from the notch 12. A counter-balance weight 13, such as a piece of cork or other light weight material, may be mounted on the free end of the lever 10 in order slightly to overcome the weight of the opposite end 15 of the lever 10. Said opposite end of the lever 10 has integral therewith a downwardly extended portion 14 bent to provide a laterally extended arm 15 that projects through a slot 16 into a relatively narrow and wide coin 20 chute 17. Thus, a coin of proper value dropped into the coin chute 17 will move downwardly the lever arm 15 and thereby oscillate said lever on the pivot 11, raising the latch 10 out of the notch 12 and permitting 25 the balls to swing the lever 8 out of the way and pass along to position opposite the opening 7 from which the balls may be removed.

An abutment 18 at the end of the inclined wall 6 stops the balls 4 opposite the opening 30 7. The distance of the lever 8 from the abutment 18 is just sufficient to permit a predetermined number of balls to pass the lever 8 and to be stopped by the abutment 18 and to 35 permit the lever 8 to swing back to its unoperated position and receive the lever 10 in the notch 12. Thus, the lever 8 becomes latched when the movement of the balls stops, said lever functioning as a counting device to permit the required number of balls to pass 40 and also as an abutment to prevent additional balls from passing after the predetermined number of balls have passed and been removed. The chute 17 is enclosed in a housing 19 attached to the end wall 20 of the table 45 and has near its upper end a coin inlet chute 21. The housing 19 encloses a coin receiving, discharging and assorting mechanism whereby coins of proper value are discharged into the chute 17 and slugs and other fraudulent 50 and spurious devices are thrown aside and discharged through another chute 22 beyond and out of communication with the chute 17. The chute 22 communicates with an opening 55 23 (Fig. 4) in the lower end wall of the housing 19 through which the slugs and spurious elements drop into a receiving hopper 24.

The coin receiving and assorting device 25 is mounted for vertical sliding movements between guides 26 and is supported by a pair 60 of springs 27. The lower ends of the springs 27 are connected with laterally extended pins 28 on the sides of the receiving and assorting device 25 and with stationary pins 29 projecting from the end wall 20 of the table. 65 Thus, the coin receiving and assorting de-

vice 25 is supported in its unoperated position in which the chute 30 in said device 25 is opposite and in communication with the inner end of the coin inlet chute 21.

Two swinging arms 31 are mounted in the chute 30 in the coin receiving and assorting device 25. These arms 31 are spaced apart and are pivotally supported at their upper ends by pins 32 spaced sufficiently to permit a coin 33 to pass between the arms 31 while the coin receiving and assorting device is in its unoperated position. The lower ends of the arms 31 have inwardly extended projections 34 onto which the coin 33 drops and by which the coin 33 is supported until the coin receiving and assorting device is moved downwardly. The lower ends of the arms 31 also have downwardly and laterally inclined arms 35 which, in the upper and unoperated position of the receiving and assorting device 25, abut against the guides 26 and thereby hold the arms 31 in position to support the coin 33. Thus, it is necessary to move the coin receiving and assorting device downwardly, so that the arms 35 are below the lower ends of the guides 26 in order to permit the arms 31 to be moved apart by the coin 33 and thereby permit the coin 33 to pass between the projections 34 and drop. The position of the arms 31 in the unoperated position of the coin receiving and assorting device is shown in Fig. 5, a coin 33 being supported thereby; and the downward position of the receiving and assorting device is shown in Fig. 6, the coin 33 having just dropped from between the arms 31 onto the weighing and assorting device, whereby coins of proper value are discharged into the chute 17 and slugs, etc. are thrown out and discharged into the chute 22.

The coin selector and slug ejector mechanism is located above the chute 17, so that the coins and slugs dropping from the receiving and assorting device drop onto said coin selecting and slug ejecting mechanism. The said mechanism comprises a pair of angular elements, one of which includes a downwardly extended arm 36 mounted on a pivot 37 and having in connection therewith an arm 38 extending obliquely inwardly and downwardly above the chute 17 and below the coin receiving and assorting device. Thus, the coin 33 dropping from the coin receiving device drops onto or against the arm 38. The arm 36 is threaded and has a counter-balance nut 39 connected therewith. A counter-balance member 40 is in adjustable screw connection with the nut 39 in order to provide for the operation of the arm 38 by a coin of true value and approximately true weight. This head 40 may be attached either before or after the counter-weight nut 39 has been screwed onto the stem 36.

The other angular member of the coin selector and slug ejector mechanism comprises

an angular member including an arm 41 mounted on a pivot 42 and connected with a downwardly and inwardly inclined arm 43. The arm 43 is in the same vertical plane with the arm 38 and is located above the chute 17 and below the coin receiving device, so that when the coin 33 is discharged from the projections 34, said coin drops into the space between the arms 38 and 43 and onto and into contact with said arms. The counter-balance weight nut 44 is screwed onto the threaded arm 41. A counter-balance member 45 is in adjustable screw connection with the nut 44 and may be adjusted so as to permit movement of the arm 43 by a coin of proper value and weight.

A slug ejector comprising a leaf spring having a portion 46 (Fig. 4) curving outwardly into the vertical plane between the chute 17 and the chute 30 is mounted in connection with the end wall 20 of the table. The bowed portion 46 of this spring extends transversely into the space above the arms 38 and 43 and into position to be engaged and pushed laterally toward the table end wall 20 and out of alignment with the chutes 17 and 30 by the rear wall of the coin receiving device 25. Accordingly, when the coin receiving device 25 is moved downwardly in opposition to the springs 27, the rear wall of said device 25 rubs against and bends the spring 46 to position out of alignment with the chutes 30 and 17, so that at the proper time the coin or slug contained in the chute 30 will push the arms 31 apart and drop onto the arms 38 and 43. If this coin is of true value and weight, it will press the arms 38 and 43 apart and drop into the chute 17 and thence onto the end 15 of the latch 10 with sufficient force to disengage the latch 10 from the lever 8 and permit the balls to roll along the wall 6 until the ball in front is stopped by the abutment 18. This permits just the required number of balls to pass, stops said balls as a series as shown in Fig. 2, and permits the lever 8 to swing back to its unoperated position in which it is engaged and latched by the lever 10.

It is a familiar fact that these spurious slugs now used extensively in order to defraud vending machines are of less weight than the coins for which they are intended to be substituted. Accordingly, a spurious slug passed into the chute 30 and discharged therefrom onto the arms 38 and 43 will not operate said arms 38 and 43 but will be supported thereby and held from passing into the chute 17. When the coin receiving device rises, it moves out of engagement with the curved spring 46 which immediately acts to throw the spurious slug from the arms 38 and 43 into the chute 22. The arm 43 extends downwardly a sufficient distance to prevent any slugs from accidentally passing into

the chute 17 and to require the slugs to pass into the chute 22.

The coin receiving device has an arm or finger piece 47 extending through a slot 48 in the housing 19, whereby the coin receiving device may be pushed downwardly in opposition to the springs 27 after the coin 33 or the slug in substitution for the coin has been passed into the chute 30. Due to angularity of the chute 30 and the usual unfamiliarity of operators with the construction of the device, it is nearly impossible to manipulate the apparatus fraudulently.

It is now clear that my invention obtains all of its intended objects and purposes in a most efficient and satisfactory manner. The construction and arrangement of the parts may be varied in numerous respects without departure from the nature and principle thereof. The device may also be applied to numerous uses other than the specific use indicated. The specific application of the device herein shown is only illustrative and the device may easily be adapted for numerous purposes without departure from the invention.

I contemplate such variations as may be required or found desirable, and what I claim and desire to secure by Letters Patent is:

1. Mechanism of the character described comprising a pair of pivotally supported coin weighing devices arranged to swing apart and discharge between them a coin of predetermined weight and value when said coin is placed thereon and to support elements of less weight than said coin, an ejector for ejecting said elements from said devices, a coin receiver for receiving and supporting said coins and said elements, and means for moving said receiver to position to discharge said coins and said elements therefrom onto said devices and to render said ejector ineffective to eject said coins from said devices and effective to eject said elements from said devices.

2. Mechanism of the character described comprising pivotally supported weighing devices for receiving and discharging between them coins of predetermined value and weight and for supporting elements of less weight than said coins, an ejector for ejecting said elements from said devices, and mechanism for delivering said coins and said elements onto said devices and causing said ejector to permit said coins to pass between said devices and to eject said elements from said devices.

3. Mechanism of the character described comprising two spaced pivotally supported weighing devices for receiving and discharging between them coins of predetermined value and weight and for supporting elements of less weight than said coins, a chute for receiving the coins discharged from between said weighing devices, an ejector for

ejecting said elements from said weighing devices, and mechanism for delivering said coins and said elements onto said devices and energizing said ejector effectively to cause said ejector to eject said elements from said devices and prevent said elements from passing into said chute.

4. Mechanism comprising a pair of angular weighing devices, means pivotally supporting said weighing devices in spaced relationship in position to receive and discharge between them coins of predetermined value and weight and to receive and support elements of less weight than said coins, mechanism for delivering said coins and said elements onto said devices, and an ejector controlled by said mechanism effectively to eject said elements from said devices and to permit said coins to pass between said devices.

5. Mechanism of the character described comprising pivotally supported weighing devices for receiving and discharging between them coins of predetermined value and weight and for supporting elements of less weight than said coins, means for adjusting said devices to perform said functions with approximate precision and certainty, an ejector for ejecting said elements from said devices, and mechanism for delivering said coins and said elements onto said devices and controlling said ejector to permit said coins to pass between said devices and to eject said elements from said devices.

6. Mechanism of the character described comprising separate chutes for receiving coins and other elements respectively, pivotally supported weighing devices for receiving and discharging between them into one of said chutes coins of predetermined value and weight and for supporting the other elements that are of less weight than said coins, an ejector for ejecting said elements from said devices into a chute other than said chute into which said coins are discharged, and mechanism for delivering said coins and said elements onto said devices and controlling said ejector to permit said coins to pass between said devices and to eject said elements from said devices.

7. Mechanism of the character described comprising a coin receiving chute, a pair of angular pivotally supported weighing devices for receiving and discharging between them into said chute coins of predetermined value and weight and for supporting elements of less weight than said coins, a movable coin receiving chute, means for supporting coins and other elements in said movable chute, an ejector for ejecting said elements from said devices, and mechanism for operating said movable chute to discharge said coins and said elements therefrom onto said devices and to control said ejector to permit said coins to pass between said devices and to eject said elements from said devices.

8. Mechanism of the character described comprising a coin receiving chute, a pair of angular pivotally supported weighing devices for receiving and discharging between them into said chute coins of predetermined value and weight and for supporting elements of less weight than said coins, a movable coin receiving chute, means for supporting coins and other elements in said movable chute, an ejector for ejecting said elements from said devices, mechanism for operating said movable chute to discharge said coins and said elements therefrom onto said devices and to control said ejector to permit said coins to pass between said devices and to eject said elements from said devices, and means for regulating and adjusting said devices to weigh and to control said coins and said elements with approximate precision.

9. Mechanism of the character described comprising pivotally supported weighing devices for receiving and discharging between them coins of predetermined value and weight and for supporting elements of less weight than said coins, mechanism for delivering said coins and said elements onto said devices, and an ejector controlled by said mechanism to permit said coins to pass between said devices and to eject said elements from said devices.

10. Mechanism of the character described comprising pivotally supported weighing devices for receiving and discharging between them coins of predetermined value and weight and for supporting elements of less weight than said coins, mechanism for delivering said coins and said elements onto said devices, an ejector controlled by said mechanism to permit said coins to pass between said devices and to eject said elements from said devices, and separate chutes for receiving said coins and said elements after said coins are discharged and said elements have been ejected from said devices.

11. Mechanism of the character described comprising pivotally supported weighing devices for receiving and discharging between them coins of predetermined value and weight and for supporting elements of less weight than said coins, mechanism for delivering said coins and said elements onto said devices, an ejector controlled by said mechanism to permit said coins to pass between said devices and to eject said elements from said devices, separate chutes for receiving said coins and said elements after said coins are discharged and said elements have been ejected from said devices, and means for regulating and adjusting said devices to weigh said coins and said elements with approximate precision.

12. Mechanism of the character described comprising a longitudinally movable chute, means for conducting coins into said chute, a pair of pivoted downwardly swinging arms

in said chute, projections in connection with said arms for supporting said coins in said chute, means holding said arms in position in which said projections will support said 5 coins when said chute is in its unoperated position and permitting said arms to be swung apart by said coins when said chute is moved to an operated position, weighing devices for receiving the coins discharged 10 from said chute and for supporting elements of less weight than said coins, and an ejector controlled by said chute to permit the coins to operate and pass between said weighing devices and to eject said elements from said 15 devices.
